UNITED STATES PATENT OFFICE

141,776

DESIGN FOR A DISK DICTATING MACHINE

Charles W. Dann, Orange, and Louis Z. La Forest,
Parsippany - Troy Hills Township, Morris
County, N. J., assignors to Thomas A. Edison,
Incorporated, West Orange, N. J., a corporation
of New Jersey

Application February 20, 1945, Serial No. 118,063

Term of patent 14 years

(Cl. D56—4)

To all whom it may concern:

Be it known that we, Charles W. Dann, a citizen of the United States and a resident of Orange, county of Essex, State of New Jersey, and Louis Z. La Forest, a citizen of the United States and resident of Parsippany-Troy Hills Township, county of Morris, State of New Jersey, have invented a new, original, and ornamental Design for Disk Dictating Machine, of which the following is a specification, reference being had to the accompanying drawing, forming part thereof.

Figure 1 is a perspective view of a disk dictating machine embodying our novel design.

Figure 2 is a view thereof in rear elevation.

Figure 3 is a view thereof in end elevation.

We claim:

The ornamental design for a disk dictating machine, substantially as shown.

CHARLES W. DANN.
LOUIS Z. LA FOREST.
